UNITED STATES PATENT OFFICE.

ROGERS M. WARWICK, OF CHICAGO, ILLINOIS, ASSIGNOR TO GENERAL WIRE TIE CO., OF CHICAGO, ILLINOIS, A CORPORATION OF ILLINOIS.

MACHINE FOR TYING OBJECTS WITH WIRE.

1,305,422.

Specification of Letters Patent.

Patented June 3, 1919.

Application filed July 12, 1915, Serial No. 39,515. Renewed November 4, 1918. Serial No. 261,158.

To all whom it may concern:

Be it known that I, ROGERS M. WARWICK, citizen of the United States, residing at Chicago, in the county of Cook and State 5 of Illinois, have invented certain new and useful Improvements in Machines for Tying Objects with Wire; and I do hereby declare the following to be a full, clear, and exact description of the invention, such as will 10 enable others skilled in the art to which it appertains to make and use the same.

This invention has for its object to provide certain new and useful improvements in machines for tying objects with wire, and 15 relates more particularly to that type of machine which is fully described and claimed in my copending applications Ser. No. 844894, filed June 13, 1914, Ser. No. 9962, filed Feb. 23, 1915, and in the joint applica- 20 tion of Warwick and Nessling, Ser. No. 22374, filed Apr. 19, 1915, and the applica- 25 tion of E. V. Nessling, filed Apr. 19, 1915, Ser. No. 22395.

The main object of the present invention 30 is to provide a machine of the character defined which includes mechanism for feeding, retracting, and cutting wire, and an object carrier associated with said mechanism which is equipped with object-engaging 35 means and with means or mechanism coacting with the aforesaid wire feeding, retracting and cutting mechanism for passing such wire around the object, the first-named mechanism being further equipped with 40 means coacting with the wire-engaging mechanism for tying the loop of wire passed about each object.

A further object of the invention is to 45 provide object-engaging means for objects of a yielding nature, such as the puckered mouths of bags, which will compress such object as tightly as possible preparatory to passing the wire-tie about the same so that the latter may be easily placed tightly about 50 the same without undue strain on the wire manipulating mechanism, and whereby the wire-tie will be made to perform the function of preventing expansion of such object without first performing the function of 55 contracting the same.

In the accompanying drawings illustrating a suitable embodiment of the present invention:

Figure 1 is a view in side elevation of a machine for tying objects with wire constructed in accordance with the invention. 55

Fig. 2 is a top plan view of the same.

Fig. 3 is a fragmentary central vertical longitudinal section of the same on the line 60 3-3 of Fig. 2.

Fig. 4 is a detail horizontal section on an enlarged scale on the horizontal plane in which the wire moves.

Fig. 5 is a detail horizontal section on the line 5-5 of Fig. 3. 65

Fig. 6 is a detail fragmentary front elevation of one of the object-engaging and wire-guiding members of the bag carrier.

Fig. 7 is a fragmentary detail vertical longitudinal section on the line 7-7 of 70 Fig. 2.

Fig. 8 is a detail vertical transverse section on the line 8-8 of Fig. 2.

Fig. 9 is a detail view in elevation of the wire tie formed by the machine about the 75 object.

Fig. 10 is a detail horizontal section on the line 10-10 of Fig. 3.

Fig. 11 is a detail horizontal section on the line 11-11 of Fig. 3. 80

Fig. 12 is a fragmentary detail top plan view of another embodiment of the object-engaging and wire-guiding mechanism of the object carrier.

Fig. 13 is a detail central vertical longitudinal section of the same on the line 11- 85 11 of Fig. 10.

Fig. 14 is a detail sectional view of the wire-bending device shown in Figs. 12 90 and 13.

The machine comprises, as aforesaid, the mechanism for feeding predetermined lengths of wire forward from a coil thereof, mechanism for engaging the outer end of the wire thus fed forward, mechanism for retracting the wire thus fed forward to an extent sufficient to draw the same relatively tightly about the object, mechanism for tying a loop of wire, and mechanism for cutting the wire and bending the end portions 100

- of the piece or loop thus cut from the body or coil thereof to form a key, all of the aforesaid mechanism being contained on what I shall term the rigid portion of the 5 frame of the machine. The machine also includes an object-carrier in the form of a turn-table which is equipped with object-engaging mechanisms with each of which there is associated means for causing the 10 wire fed forward by the feeding mechanism to be looped about the object to be tied, and which guides the extreme end of the wire into position to be engaged by the aforesaid engaging means to hold said end against retraction whereby the retracting mechanism is enabled to cause the loop of wire to be drawn tightly about the object. 15
- The mechanism for feeding the wire forward, retracting it, cutting the same, and 20 forming the key for opening the tie is substantially identical with the mechanism shown and described in my aforesaid application, Ser. No. 9962, and the wire guide for forming the loop about the object to be tied 25 is likewise similar in construction and operation, but is disposed upon the bag-carrier instead of being carried by the portion of the machine supporting the aforesaid mechanism.
- 30 In the drawings, 1 indicates the table or supporting plate for the mechanism for feeding the wire forward from the coil. Supported upon said plate is a wire guide 2 consisting of a tube through which the wire 35 is passed in engaging relation to retracting devices 3 therefor. Associated with the guide 2 is what may be termed a continuation 4 of said guide likewise consisting of a tube through which the wire passes into engaging relation to the wire feeding device 5, and it then passes through a further continuation 6 of said wire guide through which the wire is passed to project from the forward end of the machine and between clamping 40 jaws by means of which it is adapted to be twisted to close and tie the portion thereof which is passed about the object carried by the object-carrying portion of the mechanism.
- 45 The wire feeding devices 5 consist of opposed segments having roughened or knurled opposed faces adapted to engage the wire passing therebetween, said segments being carried by spur gears 7 and 8 respectively, the former being rotatable on a stud 9 rigidly mounted on the table 1, and the latter being rotatable on a stud-shaft 10 which is carried by a reciprocable plate 11 mounted in suitable guides 12 on said table 50 1. The said reciprocable member 11 comprises a plate which is normally maintained at the inner limit of its movement by means of the compression springs 13, and which, when so disposed, causes the opposed

faces of the segments 5 to be forced toward 65 each other to engage the wire disposed therebetween. The said member 11 is moved outwardly against the action of said springs 13 by means of the lever 14 and cam 15 and co-acting member 16 as will be hereinafter 70 more fully described. The said spur gears 7 and 8 are adapted to mesh and their relative separating movement is so slight as to maintain the same always in mesh. The gear 7 is driven from a source of power and 75 serves to rotate the gear 8 meshing therewith. The said gears are rotated continuously during operation of the machine, and are adapted to feed forward at intervals a length of wire equal to the length of the 80 arcs described by said segments 5 during each revolution thereof. The wire thus fed passes through the several guides 2, 4 and 6 and through the guide opening 17 in the rotatable head 18, said guide opening 17 being 85 concentric with said head at the inner head of the latter and extending at an incline therethrough so that its outer or delivery end is disposed at a distance from the axis of rotation of said head. Said discharge 90 opening is equipped with a removable guide member 19 which may be removed and replaced when worn. The length of wire fed forward is projected from said member 19 through the wire guide or wire looping member 20 which is substantially horseshoe-shaped and is disposed upon the object-carrier, and causes the extreme end of the wire 95 to be projected from its other end back toward said head 18 where it is engaged by a 100 clamp or vise comprising the opposed members 21 and 22. Both said vise-members consist of levers pivotally secured between their ends within the said head 18 and which project at their forward end or head portions from the forward end of said rotatable head or sleeve 18. The head 23 of the member 21 is flaring so as to project laterally beyond the side edges thereof; while the member 22 is one-half the width of said 110 member 21 and is provided with a head portion 24 corresponding in shape and size with one-half the head portion 23 of the member 21. The inner ends of said members 21 and 22 are disposed in the path of 115 wedge-members 25 and 26, both of which are rigid with a reciprocable head 27, the latter and said wedge portions or members 25 and 26 being reciprocable on the central partition member 29 of said sleeve or head 18 and 120 through which the guide opening 17 is bored. Associated with the said member 21 and head 23 is a second member similar to and disposed beside the member 22 and which has a head portion similar to the latter and coacting with the other side portion of the head 23 of the member 21. The said 125 last-named vise-member is not illustrated in

the present drawings, but is fully illustrated and described in the last-named aforesaid copending application. The wedge member 26 is provided at its forward end with two 5 cam surfaces, one of which engaging the said member 22 causes the head 24 of the latter to approach the head 23 of said member 21 to clamp the wire before the other co-operating vise-member, not shown, engages that 10 portion of the body of the wire disposed between the head thereof and the corresponding portion of the head 23. The head 27 carrying said wedge-members is adapted to make two separate forward movements 15 at respectively different intervals, the first of same being sufficient to cause the head portions 23 and 24 to engage the wire while leaving the other vise member, not shown, out of engaging relation to the wire disposed 20 between the head thereof and opposed portion of the head 23, these movements of said head being accomplished by means of a cam rotatable with the gear 7, as will be hereinafter more fully described, and as is 25 fully described and claimed in my last-named aforesaid pending application.

From the foregoing it will be seen that the wire is fed forward in a given length from the coil at regular intervals by means 30 of the segments 5 and that the wire thus passed forward is projected from the member 19 through the guide 20, and the forward end of the wire then passed between the jaws 23 and 24, which thereupon close upon 35 said end of the wire and firmly hold the same. The object to be tied is, as will be hereinafter more fully described, contained within the said wire guide 20 so that the horseshoe shaped loop of wire formed by 40 the guide 20 will be disposed around such object. The wire is now retracted by means of the retracting devices 3 so as to withdraw the loop of wire from the guide 20 and cause the same to close tightly about the object.

45 The retracting means comprises, as aforesaid, the two members 3, each of which is a segmental gear. One of these is pivotally mounted on a stud 29 rigidly mounted on the table 1, and the other of which is pivotally mounted on a stud 30 carried by the reciprocable member 11. Both said members 3 are equipped with wire-engaging segments 31 similar to, but of less length than, the segments 5, and which are similarly 50 equipped with wire-engaging faces roughened to secure a positive hold on the wire. One of said members 3 is equipped with an L-shaped projection 32 carrying a rod 33 on which a helical compression spring 34 is 55 coiled, the latter bearing at one end against an arm of a bell-crank lever pivotally mounted at its elbow on the member 11 and the other arm 36 of which is disposed in the 60 path of a projection 37 carried by the said

gear 8 whereby it is moved against the action of the spring 34, thus compressing the latter and causing it to rotate the said member 3 by which it is carried. Said members 3 have intermeshing gear teeth whereby they are caused to oscillate in unison and the spring 34 thus determines the tension to be imparted to the wire retracted by said members 3, as will be obvious. The length of wire retracted will be determined primarily by the diameter of the object about which the loop of wire is drawn, it being obvious that the same tension will be imparted to the wire about an object of smaller as about an object of larger diameter. The said wire-engaging segments 31 are drawn out of engaging relation to the wire by means of the lever 14 and the cam and companion member associated therewith heretofore referred to for reciprocating said member 11. Normally, however, the wire feeding and reTRACTING means are maintained in engaging relation to the wire by means of said springs 34 as will hereinafter more fully appear. The said segments 3 oscillate freely and are drawn by the wire to the forward limits of their oscillatory movement as the wire is fed forward by the segments 5.

The said head 27 is provided with an annular groove in which anti-friction rollers in the forked end of a rocking lever 37 engage; said lever being pivotally secured to a stud 38 on the table 1, and being provided with a projection 39 carrying an anti-friction roller engaged in the cam groove 30 in the said gear 7. It will be seen that said cam groove is provided at one point with two stepped portions 41 and 42 respectively, the retraction of the wire taking place during the time that the said anti-friction roller is disposed in the stepped portion 41, and, as the same becomes disposed in the stepped portion 42, the aforesaid additional vise member, not shown, is thrown to engage the body of the wire between the head thereof and the opposed portion of the head 23. Said wire is now maintained so clamped at two points until the anti-friction roller on said projection 39 passes into the stepped portion 43 of said cam groove 30 whereupon the vise jaws are all returned to the position shown in Fig. 3, the same being normally held in such position by means of the compression spring 44.

The next operation taking place is that of twisting the portions of the wire disposed between the object and the vise jaws about each other to tie the loop formed about the object. This is accomplished by rotating the head or sleeve 18 while the vise jaws are still engaged with the wire, and while the loop formed by the latter is engaged with the object, as heretofore pointed out. The rotation of said head or sleeve 18 is effected by means

- of the spur-pinion 45 rigid with the said head or sleeve 18, and which meshes with a spur-gear 46 on a shaft 47 journaled in a bearing 48 carried by said table 1. The other end of the shaft 47 carries a bevel-pinion 49 which is adapted to mesh with the segmental bevel-gear 50 rigid with the spur-gear 8 and which projects outwardly from the periphery thereof. The number of teeth 10 of said segmental gear 50 and the bevel pinion 49, and the ratio of the spur gear 46 to the spur pinion 45, are such as to cause the said sleeve or head 18 to make a predetermined number of revolutions which, in the 15 instance illustrated, is three complete revolutions for each revolution of the spur gear 8. The time or interval in which the rotation of said head or sleeve 18 takes place is so timed relatively to the interval in which the anti-friction roller of the arm 39 is engaged in the portion 42 of greatest radius of the cam groove 40, as to cause said revolution of said head or sleeve 18 to be completed substantially simultaneously with the passage of 20 said anti-friction roller of said arm 39 out of said portion 42 in said cam groove and into the portion of least radius thereof, the latter constituting the main portion of said groove.
- 25 The next operation is that of bending the ends of the wire constituting the outer portions of the tie to form the key 51 which may be digitally engaged to untwist or open the loop, as clearly shown in Fig. 9. This operation also includes the severing of the tie, now formed and completed, from the body of the wire at the discharge end of the member 19. It will be observed that the vise jaw heads 30 and 24 are provided with coacting cylindrical projections 52 between which the wire is engaged, the body portions of said vise jaw heads being separated from each other by an open space. The said projections 52, are when the jaw members are closed in engagement with the wire, disposed in the path of dogs 53 carried by a laterally reciprocable plunger 54, the latter being fully described and claimed in my last-named aforesaid application. This plunger 54 is provided between its ends with an opening through which the said heads of the vise members project, the said dogs being supported midway between the upper and lower walls of said opening in a suitable manner. Each of 35 said dogs consists of a small bell-crank lever pivotally supported at its elbow portion, and having its shorter arm projecting outwardly into engaging relation to the said projections 52, the longer arms being adapted to 40 swing toward the object embraced by the loop as said shorter arms engage the said projections 52, as will be obvious. The said plunger also carries a wire severing edge or knife not shown in detail in the accompanying drawings, which is adapted to shear the
- wire at the mouth of the member 19. The said plunger 54 is connected by means of a link 55 with one end of a lever 56 pivotally mounted between its ends on the stud 38, and which is provided at its other end with 45 an anti-friction roller 57 engaged in a cam groove in the lower face of the gear 7, the said cam groove 58 being illustrated in dotted lines in Fig. 4. The said groove is provided with two stepped portions 59 and 60, the first of which is adapted to throw the anti-friction roller radially outwardly from the axis of rotation of the gear 7 whereby the said plunger 54 is moved in one direction, and the stepped portion 60 being adapted to 50 throw the anti-friction roller 57 radially inwardly a distance practically double the distance of its outward throw whereby to move the plunger in the opposite direction a distance sufficient to cause the other dog to bend 55 the contiguous end of the wire tie immediately following the shearing of said end of the wire from the body thereof. This bending and shearing operation takes place just preceding the opening of the vise jaws 23 60 and 24 to release the wire, and the tie is then complete, and the operation aforesaid repeated.
- In order that the vise jaws may always resume and hold their normal positions between the intervals of rotation of the head or sleeve 18, the said spur gear 46 is provided with a recess 61 in which the head of a plunger 62 is adapted to engage to hold said spur gear against rotation, said plunger being 65 held normally in engaging relation to the gear by means of a spring 63. The body portion 64 of said plunger is reciprocable in guides in the base of the standard for the bearing 48 as clearly shown in Fig. 7. 70 Mounted at the outer end of said portion 64 of said plunger is an anti-friction roller 65 which is disposed in the path of a cam projection 66 formed on the inner face of the bevel gear segment 50, and which engages 75 said anti-friction roller to withdraw said plunger from engagement with said spur gear 46 just preceding the intermeshing of the said bevel segment 50 with the bevel pinion 49 and holds the same out of engagement 80 therewith until the said intermeshing parts have passed out of meshing relation to each other, thereby causing the said plunger to spring into locking engagement with the spur gear 46 at the moment that the rotation 85 thereof by said gearing has been completed.
- While the mechanism above described is not shown in as great detail as may be necessary to a perfect understanding of the same, it will be understood that reference may be 90 had to such details as are omitted from particular illustration, to the aforesaid last-named copending application.
- Having now described the first-named mechanism or mechanisms for manipulating 95

the wire I will proceed to describe the coacting object-carrying mechanism associated with said wire-manipulating mechanism.

The said object-carrying mechanism is particularly adapted to receive and engage the puckered mouths of bags such as are used for packing cement, cereals, flour and the like, but may obviously be constructed to adapt the same to receive and carry objects of any other kind to be tied with wire, such for example, as milk bottles, jars, laths, dowel sticks, implement handles, and the like.

The said carrying mechanism is supported on brackets 67 mounted upon the frame supporting the table 1 and opposite the discharge end of the wire-feeding mechanism. Said brackets are connected together by means of a substantially semi-circular frame-piece 68 and a cross-bar 69. Supported at one end upon the middle portion of the member 68 and at its other end upon the bearing for the rotatable head or sleeve 18 and between its ends upon the cross-bar 69 is a member 70 which is provided between its ends with a recess 71 adapted to be closed by means of the cover plate 72. The said member 70 carries the bearing 73 for a spindle 74 which also extends through a sleeve 75 journaled in a bearing 76 on said member 72. Said sleeve 75 is keyed or otherwise maintained rigid with said spindle 74 so as to rotate therewith and is provided at its lower end with an annularly enlarged flanged portion 77, the inner peripheral face of said flange being equipped with ratchet teeth 78. Rotatably mounted on said spindle 74 between the ends thereof is a spur pinion 79, the hub of which carries a disk 80 which fits telescopically within the said flange 77 of the sleeve 75 and carries a pair of spring-actuated pawls 81 adapted to engage the said ratchet teeth 78. The said spur pinion 79 rests upon the bottom of the recess 71 in the member 70 and meshes with the segmental gear 82 at the outer end of an arm or lever 83 which is pivotally mounted upon the inner end portion of the bearing for the sleeve 18. The said spindle 74 is supported at any desired elevation by means of the nut 84 engaging the threaded reduced upper end 85 of said spindle and resting upon a cap plate 86 loosely rotatable on the bearing 76, a ball-bearing 87 being provided within the annularly enlarged upper end portion of said bearing 76 for rotatably supporting the said spindle in a well-known manner. At its lower end said spindle carries a U-shaped guide member 88 having three radial hollow arms 89 in each of which there is reciprocably mounted a sleeve 90, the latter being suitably held against rotation therein. Each of said sleeves 90 carries a head 91 having a U-shaped arm, the upper end portion of which is equipped with a projection 92, and is also equipped with a pair of outwardly extending arms 93 bordering a recess, which is substantially semicircular, in which the object to be tied is adapted to be received. A spring 94 bearing at one end against the hub of said member 88 and at its other end against the portion of the head 91 engaged in the sleeve 90 maintains said sleeve normally at the outer limit of its movement relative to the arm 89 in which it is reciprocably mounted.

Associated with each of said heads 91 and sleeves or arms 89 are means adapted to coact with the arms 93 for engaging an object to be tied, said means comprising a pair of arms 95, each of which is pivotally secured at one end by means of the bolts 96 upon one of said arms 89 at opposite sides of the horizontal plane of its axis, said arms terminating at their outer ends in converging projections 97 adapted to coact with the recess bordered by the arms 93 for providing a substantially circular opening through which the object to be tied, such as the puckered mouth of a bag, is adapted to extend, and in which it is firmly held during the tying operation. Each of said arms 95 is provided with an outwardly extending projection 98 provided with a perforation into which a rod 99 projects, the latter being pivotally secured at its other end to the end portion of a side flange 100 integral with the sleeve or arm 89. Helical compression springs 101 are coiled about said rods 99 and serve to normally maintain the said arms 95 disposed in closed position as shown in the left-hand side of Figs. 10 and 11. Said arms 95 are also provided on their inner or opposed faces or edges with projections 102, each of which has that face opposing the pivotal axis of the arm disposed at an incline to the side edge of such arm so that the two edges of the opposed pair of projections 102 together constitute a slightly V-shaped surface which is adapted to engage in a similar recess 103 in the forward edge of the projection 92 of the head 91, when the latter is disposed to engage an object of the smallest periphery which the machine is adapted to tie, and which constitutes stops to limit the forward movement of said head 91 to engage an object between the head 93 and the arms 97. Integral with the hubs of said arms 95 are intermeshing gear segments 104 which cause them to swing in unison in respectively opposite directions. One of said arms is further provided with an integral projection 105 carrying an anti-friction roller 106 adapted during the rotation of the member 88 to engage a cam 108 for opening the arms 95 against the action of said springs 101. Said cam 108 is carried by the member 70 and is rigid therewith, and is disposed in proper position in the path of

said anti-friction rollers 106 for releasing and engaging the same at proper points in their travel to perform the aforesaid functions synchronously with relation to the 5 operations of the tying mechanism.

Each of said arms 95 also carries one member 109 of a wire guide or wire-bending device, the latter being practically horse-shoe-shaped or V-shaped and comprising 10 two equal parts adapted to contact and register with each other at their middle portions to provide a continuous structure, and which is provided with a channel of the same shape into which the wire is adapted 15 to be projected at one end to be bent in passage therethrough to surround or partially surround the object to be tied which projects through said wire guide, and from which the wire is adapted to be drawn tightly 20 about such object upon the operation of the wire-retracting mechanism heretofore described. Said wire guide may be variously constructed, but as shown in Figs. 6, 7 and 8 it is shown as constructed and operated sub- 25 stantially as shown and described in my aforesaid application for patent, Ser. No. 844,894 that is to say, the lower members of each of the parts 109 of said guide are rigid with the arms 95, while the upper or 30 cover-plate members of said guides are hinged to said lower parts so that the pivotal axis is substantially parallel with the straight portion or arm of the lower member, and is held to normally rest upon the 35 lower member by means of a spring 110, as clearly shown in Fig. 6. The wire loop is withdrawn from said guide by the retracting mechanism against the action of said springs 110, that is to say, it is practically 40 forcibly sprung out of the guide against the action of said springs.

Associated with said carrier, as clearly shown in Fig. 2, is a slotted guide member 111 in which the mouth portion of a bag is 45 adapted to be received and supported, the same being moved by hand through said guide slot until one side edge portion of the bag projects into the recess bordered by the arms 93 of the head disposed in alignment 50 or receiving relation to said guide 111. Pivotaly mounted upon one of the brackets 67 is a lever 112, the outer end portion of which is adapted to swing through an arc intersected by the guide slot of the member 111, 55 said arm being adapted to engage the outer edge portion of the bag and, as it turns on its pivot, is adapted to force the mouth portion of the bag into the aforesaid recess bordered by the arm 93, thereby also puckering 60 the same and exerting a sufficient pressure upon the said puckered portion of the bag to force the head 91 inwardly against the action of the spring 94. It will be seen that the inner ends of the projections 102 bear 65 against the side edges of the projection 92

when the said head 91 is at the outer limit of its movement and the arms 95 are in their open position, thus maintaining the latter in said position against the action of said spring 101. As the puckered mouth of the 70 bag or other object is forced by said arm 112 into the recess bordered by the arms 93 and the said head 91 is thus forced to the inner limit of its movement against the action of the spring 94 the said projection 92 will pass 75 inwardly out of the path of said projections 102 thus permitting said arms 95 to move into closed position thereby causing the arms or projections 97 to close the recess bordered by the arms 93 and prevent the escape of the 80 object therefrom, the head 91 being now held at an inner point in its movement by the object, the latter being thus compressed between the head 93 and the projections 97.

The said lever 112 is connected at its other 85 end by means of a link 113 with an arm 114 of a member which also carries the aforesaid arm 83 and carries an additional arm 115, the latter being provided at its outer end with an anti-friction roller adapted to engage in the cam groove 116 on the gear 8, said cam serving to rock said arms 83 and 114 simultaneously. It will be seen by reference to Fig. 2 that as the lever 112 is rocked or swung in the direction to force an 95 object into engaging relation to the bag carrier, the said arm 83 is swung to turn the spur pinion 79 in a direction in which the said dogs or pawls 81 are adapted to pass freely over the ratchet teeth 78 so that during this movement of said arm 83 the said member 88 will be retained in a fixed position, but upon the rocking of the arm 83 in the opposite direction the spur pinion 79 will be turned to cause the pawls carried 100 thereby to engage said ratchet teeth to impart a rotary movement to said head 88 through an arc of one hundred and twenty degrees, thereby causing the object fed to said carrier to be moved into position 105 relative to the tying mechanism to be tied. The said member 88 is held rigidly in position during the first-named movement of the arm 83 and lever 112 by means of a locking device illustrated in Fig. 5, which 110 consists of a bell-crank lever 117 which is pivotally secured to the cap portion or member 72 at its elbow portion and is provided at the end of its longer arm with a projection 118 adapted to engage consecutively in 115 the three several openings 119 in the flange 77 of said sleeve 75, the shorter arm 120 of said bell-crank lever being disposed in the path of a projection 121 on said arm 83, so that as the latter rotates the spur pinion 79 120 during the feed movement of the lever 112, the said projection 121 will strike said arm 120 to cause the projection 118 to be withdrawn from the opening 119 in which it is 125 then engaged and to be held out of engage- 130

ment therewith. As soon as the said arm 83 begins to make its return movement the said pawls carried by the spur pinion 79 will engage the ratchet teeth so as to immediately 5 rotate the member 88 thereby causing the opening 119 in which said projection 118 was last engaged to move out of the path of said projection, so that by the time the latter has returned to its normal position by 10 the release of engagement of the projection 121 therewith it will merely bear upon the outer circumferential wall of said flange 77 and will spring into the next succeeding opening 119 as the said member 88 completes 15 its movement through the said arc of one hundred and twenty degrees. Upon the completion of each of said movements of said member 88, one of the said wire guides or wire-bending devices will be brought into 20 register with the discharge opening of the member 19 so that the wire projected through the latter will enter the opposing mouth of said wire guide thereby causing the loop of wire to pass around the object 25 preparatory to being drawn around the same by the retracting mechanism, as will be readily understood. The tie is then completed, as previously described, and the carrier then rotates again through an arc of 30 one hundred and twenty degrees, and during this rotation the object-engaging mechanism of the carrier now carrying the tied object is released from engagement with the latter by the engagement of the anti-friction roller 35 106 of one of its arms 95 with said cam 108, thereby causing the object to be ejected therefrom. The said object-engaging mechanism now remains open until it again becomes disposed opposite the feed slot of the 40 member 111 and receives another object.

In connection with the tying and bag-carrying mechanisms of the present machine I also prefer to employ the means for automatically throwing the wire-feed mechanism 45 into engaging relation with the wire to be projected, only when an object is presented by the carrying mechanism to the wire-tying mechanism to be tied. This mechanism is fully described and claimed in the aforesaid 50 application of E. V. Nessling, and consists of the aforesaid lever 14 which is equipped contiguous to its pivotal connection with the plate 11 with the cam member 15 adapted to engage an associate member 16 for moving the plate 11 outwardly against the action of the springs 13 when said lever is moved to the forward limit of its movement. It is held in this position normally by means of a helical tension spring and 55 thus maintains the wire-engaging mechanism of the tying machine out of engaging relation to the wire and is moved against the action of said tension spring to the position or substantially the position shown in 60 65 Fig. 4, by the object presented by the carrier

to be tied; thereby causing said wire-feeding mechanism to be moved by the springs 13 into engaging relation with the wire and causing the latter to be fed to tie the object. It will be understood, of course, that this 70 lever and the mechanism last-described constitutes no part of the present invention.

The object-engaging devices on the bag-carrier may also be constructed as shown in 75 Figs. 12 and 13 in which the member 122 corresponding to the member 88 is provided with a flat annular flange 123 upon which there is rigidly mounted a plate 124 carrying the wire guide 125 which consists of a single inseparable substantially horseshoe-shaped piece of metal having a wire guide groove 125a in its concave face. Said plate 124 is provided midway between its side edges with a guide-slot 126 in which the guide shoe of the plunger 127 is longitudinally movable, the latter being equipped at its outer end with a projection 128 in which a rod 129 is mounted, the latter projecting at its other end through the projection 130 on a plate 131 mounted on the studs 132. 80 The latter constitute the pivots of opposed object-engaging members 133 corresponding to the arms 95 in purpose and general features of construction. Said arms are maintained normally in the position shown in 85 Fig. 12 by means of a spring 134 engaged at the outer ends of its arms with the outer end portions of the arms 133, and which is provided with two coils through which said studs 132 pass. A compression spring 135 90 carried by the rod 129 maintains the plunger 127 normally at the forward limit of its movement, the forward end portion of the same normally overhanging the middle portion of the guide 125 and being thus in the 95 path of the object. Said plunger is adapted to be forced back to the position shown in Fig. 12 against the action of said spring 135 by pressure exerted thereon by the object received within said wire guide 125 as said object is forced into the latter by the lever 112, and thus permits the object-engaging members 133 to close to retain said object within the said wire guide 125. Said members 133 100 are provided with projections 136 which enter the recesses in opposite sides of said plunger 127 when said members move to closed position, and which engage the side faces 137 of said plunger when the latter is disposed at the forward limit of its movement.

The aforesaid wire-guide member 125 for bending the wire to loop formation around the object may also be made as shown in 105 Figs. 13 and 12, reference to which shows that the said guide is made of a substantially cylindrical rod provided with a continuous recess 138 having an open mouth portion through which the wire may be 110 easily withdrawn. The straight end portion 115 120 125 130 135 140

tions of this groove 138 have their upper walls cut away and are overhung by flat springs 139 which are secured at one end each to the plate 124 and rest at their free ends upon the bottom walls of said groove; the ends of said springs being equipped with lips 140 which are adapted to be sprung up by the wire as the latter is drawn out of the said groove by the action of the retracting mechanism.

10 The operation of the machine will be readily understood from the foregoing description, and a review of the same is therefore deemed unnecessary.

15 I claim as my invention:

1. In a machine of the kind specified, a traveling carrier for objects to be tied, object-engaging devices carried thereby, a wire bending element associated with each of said devices, means for feeding wire longitudinally carried by a rigid part of the machine, said bending means coacting with said feeding means for looping the wire about the object.

25 2. In a machine of the kind specified, a traveling carrier for objects to be tied, object-engaging devices carried thereby, a wire guide associated with each of said devices, means for feeding wire longitudinally carried by a rigid part of the machine, said wire guide coacting with said feeding means for looping the wire about the object.

35 3. In a machine of the kind specified, the combination with mechanism for feeding wire longitudinally at predetermined intervals, of a traveling carrier for objects to be tied adapted to present objects successively to said feeding means, object-engaging devices on said carrier, and means associated with each of the latter for causing the wire fed to form a loop about the object to be tied.

45 4. In a machine of the kind specified, the combination with mechanism for feeding wire longitudinally at predetermined intervals, of a traveling carrier for objects to be tied adapted to present objects successively to said feeding means, object-engaging devices on said carrier, and a wire guide associated with each of the latter for causing the wire fed to form a loop about the object to be tied.

55 5. In a machine of the kind specified, the combination with mechanism for feeding wire longitudinally at predetermined intervals, of a traveling carrier for objects to be tied adapted to present objects successively to said feeding means, object-engaging devices on said carrier, and a wire guide associated with each of the latter for causing the wire fed to form a loop about the object to be tied, the latter provided with an open wire-receiving groove from which the loop of wire is adapted to be drawn without distortion thereof.

6. A machine of the kind specified, including wire feeding mechanism, and a carrier for objects to be tied, means for imparting intermittent movement to said carrier at regular intervals corresponding to the intervals of activity of said wire-feeding mechanism, object-engaging means on said carrier, mechanism for feeding objects thereto during the intervals of rest of said carrier, locking means for maintaining said carrier immovable during said intervals, and means for releasing said locking means preparatory to movement of said carrier.

7. In a machine of the kind specified, an object-carrier, and object-engaging mechanism carried thereby including a reciprocable member spring-held to resist entrance of an object into engaging relation to said mechanism, coacting object-retaining elements adapted to prevent ejection of the object by said reciprocable member, mechanism for forcing the object against the latter and into engaging relation to said object-retaining elements, and means for effecting movement of the latter out of engaging relation to the object for ejecting the latter.

8. In a machine of the kind specified, an object-carrier, and object-engaging mechanism carried thereby including a reciprocable member spring-held to resist entrance of an object into engaging relation to said mechanism, coacting object-retaining elements adapted to prevent ejection of the object by said reciprocable member, springs normally holding said elements in engaging relation to the object, mechanism for forcing the object against the latter and into engaging relation to said object-retaining elements, and means for effecting movement of the latter out of engaging relation to the object for ejecting the latter against the action of the springs holding the said elements.

9. In a machine of the kind specified, an object-carrier, and object-engaging mechanism carried thereby including a reciprocable member spring-held to resist entrance of an object into engaging relation to said mechanism, coacting object-retaining elements adapted to prevent ejection of the object by said reciprocable member, projections on said elements adapted to abut against the sides of said reciprocable member when the latter is in its normal position and adapted to be disposed in the path of the same when it is disposed at the inner limit of its movement, mechanism for forcing the object against said reciprocable member to force the latter toward the inner limit of its movement whereby to permit said retaining elements to move into engaging relation to the object, and mechanism for moving the said elements out of engaging relation to said object and to

position to permit said reciprocable member to spring forward to eject said object.

10. In a machine of the kind specified, an object-carrier, and object-engaging mechanism carried thereby including a reciprocable member spring-held to resist entrance of an object into engaging relation to said mechanism, coacting object-retaining elements adapted to prevent ejection of the object by said reciprocable member, projections on said elements adapted to abut against the sides of said reciprocable member when the latter is in its normal position and adapted to be disposed in the path of the same when it is disposed at the inner limit of its movement, mechanism for forcing the object against said reciprocable member to force the latter toward the inner limit of its movement whereby to permit said retaining elements to move into engaging relation to the object, springs for normally maintaining said elements in the last-named position, and mechanism for moving the said elements out of engaging relation to said objects against the action of said springs, and to position to permit said reciprocable member to spring forward to eject said object.

11. In a machine of the kind specified, the combination with wire feeding and tying mechanism, of an object-carrier provided with a plurality of object-engaging mechanisms each including a wire-bending element adapted to be presented successively to said wire-feeding mechanism, and means associated with said bending element for holding the object in position relatively thereto to cause the loop of wire bent thereby to be formed about the object.

12. In a machine of the kind specified, the combination with mechanism for projecting a length of wire, of an object-carrier equipped with a plurality of object-engaging mechanisms, each of the latter including a wire bending guide-member in which the object is adapted to be received, said guide-member having an open wire-guide channel having its mouth opposing the object and adapted to bend the wire into a loop about said object, mechanism for effecting withdrawal of the loop of wire from said channel to draw the same tightly about the object, and means associated with the first-named mechanism for tying the loop and severing the same from the body of the wire.

13. In a machine of the kind specified, an object-carrier equipped with object-engaging mechanism including a reciprocable member

spring-held at the outer limit of its movement, a pair of laterally movable members adapted to be moved simultaneously toward and from each other and spring-held at the inner limit of their approaching movement, projections on the said member normally opposing the said reciprocable member and coacting with the latter to clamp an object, and mechanism for opening said laterally movable elements, whereby to effect release and ejection of the object.

14. In a machine of the kind specified, an object-carrier equipped with object-engaging mechanism including a reciprocable member spring-held at the outer limit of its movement, a pair of laterally movable members adapted to be moved simultaneously toward and from each other and spring-held at the inner limit of their approaching movement, projections on the said member normally opposing the said reciprocable member and coacting with the latter to clamp an object, means for inserting an object between the said laterally movable members against the action of said reciprocable member, and mechanism for opening said laterally movable elements, whereby to effect release and ejection of the object.

15. In a machine of the kind specified, an object-carrier equipped with object-engaging mechanism including a reciprocable member spring-held at the outer limit of its movement, a pair of laterally movable members adapted to be moved simultaneously toward and from each other and spring-held at the inner limit of their approaching movement, projections on the said member normally opposing the said reciprocable member and coacting with the latter to clamp an object, means associated with said reciprocable member for holding said laterally movable members at the outer limits of their movement, means for inserting an object between the said laterally movable members against the action of said reciprocable member whereby to move said means to permit closure of said laterally movable members, and mechanism for opening said laterally movable elements, whereby to effect release and ejection of the object.

In testimony whereof I have signed my name in presence of two subscribing witnesses.
